COPOLYMERIZATION OF BUTENES AND PROPENE

Frederick E. Frey, Bartlesville, Okla., assignor to
Phillips Petroleum Company, a corporation of
Delaware

Application November 21, 1939, Serial No. 305,549

6 Claims. (Cl. 260—683.15)

1

This invention relates to the manufacture of volatile hydrocarbon oils, and in particular to the manufacture of hydrocarbons whose molecules are highly branched in structure and peculiarly suitable for motor fuel in internal combustion engines where aliphatic characteristics and high antiknock value are important. It relates more specifically to the production of valuable motor fuel from isobutane, or from a mixture of hydrocarbons containing isobutane as the essential constituent, and represents a continuation of the work disclosed in Patent No. 2,116,723, entitled "Process for manufacturing hydrocarbon oils," of which I am a co-inventor.

It is an object of this invention to produce normally liquid hydrocarbons from hydrocarbons having low molecular weights.

It is also an object of this invention to produce hydrocarbons in the motor fuel boiling range which have good antiknock characteristics.

It is a further object of this invention to produce a paraffinic motor fuel having good antiknock characteristics from normally gaseous paraffin hydrocarbons.

An object of this invention is to produce highly branched, aliphatic hydrocarbons boiling in the motor fuel range from a mixture containing propene and at least one butene.

Further objects and advantages will become apparent as the following disclosure and discussion proceed.

It has been shown that, when used as fuel for internal-combustion engines, especially those of the spark-ignition type, various hydrocarbons have quite widely different combustion and detonation characteristics. Thus, in general, olefin hydrocarbons are less likely to produce or cause detonation when used as a fuel than are the corresponding paraffin hydrocarbons. Even among one given class of hydrocarbons, such as the paraffins for example, the various individual hydrocarbons differ widely among themselves as to their combustion characteristics. This is exemplified by the detonation characteristics of normal heptane and of isoctane (2,2,4-trimethylpentane), the well known standards used for evaluating detonation; the first causing detonation to a considerable extent and having, by definition, a rating of zero octane number, and the latter causing little if any detonation, even in engines having quite high compression ratios, and having by definition a rating of 100 octane numbers. Even hydrocarbons belonging to the same class and having the same molecular

weights have widely different detonation characteristics; as exemplified by various heptanes.

Hydrocarbon	Octane No.
Normal heptane	0
2-Methyl hexane	55
3-Methyl hexane	65
2,2-Dimethyl pentane	80
2,3-Dimethyl pentane	94
2,4-Dimethyl pentane	80
3,3-Dimethyl pentane	98
2,2,3-Trimethyl butane	116
3-Ethyl pentane	68

There is considerable advantage to be gained from using fuels with good antiknock qualities, inasmuch as only fuels which can be so classified can be used in engines with high compression ratios. It is well known that it is possible to obtain a high thermal efficiency in such an engine, and it has been found that the potential power to be obtained using an engine operating, in each case, at the highest permissible compression ratio, may be 50 per cent greater with a given hydrocarbon with high antiknock qualities as a fuel than when using an isomeric hydrocarbon with lower antiknock qualities. As an example, the maximum possible compression ratio of an engine using normal heptane as a fuel is about 3:1, while with its isomer, 2,2,3-trimethyl butane, the maximum ratio is about 13:1. An engine with the latter compression ratio would actually not operate if normal heptane were the fuel.

I have discovered that a valuable motor fuel, consisting essentially of highly branched aliphatic hydrocarbons, and having very good antiknock characteristics, may be prepared from isobutane, or normal butane, or from mixtures of butanes and especially those rich in isobutane in a new and novel process to be hereinafter set forth. This is accomplished by a novel combination of the dehydrogenation of the hydrocarbons charged to the process, whereby not only butenes but also an appreciable amount of propene is formed, a separation of these olefin hydrocarbons from lower boiling material, and the submission of these olefins to catalytic polymerization, in the presence of appreciable amounts of propene which has passed unreacted through the catalytic polymerization step and is recycled back to the polymerization step. The hydrocarbons produced in the polymerization step are in the motor fuel boiling range, are highly branched, are essentially olefinic and have excellent antiknock characteristics. These hydrocarbons,

or certain portions or fractions of them, can be used directly as motor fuel, and generally as premium motor fuel, especially when blended with straight run or natural gasolines, or the like. Also, inasmuch as these hydrocarbons are highly branched, the corresponding paraffins also have excellent antidentalating characteristics. It is also a part of my process that hydrocarbons produced by the catalytic polymerization step can be non-destructively hydrogenated, producing a saturated hydrocarbon product. The dehydrogenation step, which may be either thermal or catalytic or a combination thereof, produces considerable amounts of free hydrogen, and generally an amount sufficient to hydrogenate all the unsaturated hydrocarbons in the motor fuel boiling range produced in the catalytic polymerization step. When my process is operated to produce saturated hydrocarbons in the motor fuel boiling range, it is possible to operate it so that the dehydrogenation step is combined with the hydrogenation step and produces the free hydrogen which is consumed in this step.

I may also operate my process on a charge stock containing propene and butenes from an outside source, such as cracking-still gases, vapor recovery gases from a refinery wherein cracking and/or reforming operations are carried out, and the like. With such a charge stock, wherein the propene to butenes ratio, on a molecular basis, is preferably greater than 0.5:1, the hydrocarbon mixture is passed to the polymerization step, with or without additional separation, but with the addition of recycle propene, the polymerization of the olefins is carried out as has been discussed, butane is separated from the effluent of the polymerization and is dehydrogenated, hydrogen-containing gases are separated and a mixture containing catalytically polymerizable olefins, such as propene and butenes, is passed to the catalytic polymerization step.

In the catalytic polymerization of propene and butenes, it is desired that optimum amounts of hydrocarbons in the motor fuel boiling range be formed, the optimum amounts being determined with a consideration for antidentalating qualities and boiling range as well as for per cent of yield based on the charge stock. In many instances there will be formed, by the polymerization, hydrocarbon polymers which have boiling points or ranges too high to be included as a part of the motor fuel product, depending somewhat on the specifications to which the motor fuel is made as well as upon the operating conditions of the polymerization step. It is also a part of my invention to subject hydrocarbon polymers so produced and boiling above the desired motor fuel range to a depolymerization to produce hydrocarbons having lower boiling points, some of which will be in the motor fuel boiling range, and to incorporate these latter hydrocarbons as a part of the total product. Concomitantly there will also be produced gaseous olefin hydrocarbons, which can be incorporated with the charge stock to the polymerization step.

In one modification of operating my process, I prefer to use a charge stock consisting essentially of isobutane. With this modification, I can employ thermal dehydrogenation as the first step in a very satisfactory and economical manner, producing a maximum of olefins which can be catalytically polymerized with little if any olefinic material such as ethylene. These olefins consist primarily of propene and isobutene with only minor amounts of other hydrocarbons, be-

sides methane in an amount substantially equivalent to the propene, and unreacted isobutane. The effluent of this dehydrogenation is passed to separating means, and a hydrocarbon fraction is readily separated which consists essentially of propene, isobutene, and isobutane, and this mixture is sent to the catalytic polymerization step. In such a case, I prefer to operate under conditions such that propene is only slowly polymerized with itself, whereby I have found that copolymerization between propene and isobutene takes place forming highly branched heptenes and decenes and the like, along with isoheptenes and isoctenes. This is especially true of these polymerization conditions are established along with a relatively high ratio of propene to butene.

I establish and maintain such a ratio in the following manner. When the operation of such a process is started, the ratio of propene to isobutene will be low, and I have found that appreciable amounts of the propene will pass through the polymerization step unreacted. I now separate this unreacted propene from the effluent of the polymerization and return it to the inlet. Thus, in the succeeding period of operation, the ratio of propene to isobutene will be somewhat higher, and a little more of the propene will enter into the reaction. I continue this procedure, until the ratio of propene to isobutene is sufficient to insure that the amount of propene which enters into the polymerization reaction is substantially the same as the amount of propene charged to this step, exclusive of the recycled propene, but at the same time, with an appreciable amount of unreacted propene in the effluent of this step, which is recycled to the charge to the polymerization. In operating such a process I prefer that substantially all the butenes charged to the polymerization step shall enter into polymerization reactions, so that although the effluent of the polymerization step will contain appreciable quantities of unreacted propene, it will contain little if any unreacted isobutene or other butenes. Thus my process is most satisfactorily operated when the polymerization conditions of temperature and pressure are such that propene is only slowly polymerized with itself, and the reaction time is such that the effluent contains very little unreacted butenes.

With these limitations and novel features, this part of my invention readily distinguishes over conventional polymerization steps wherein the olefins charged are incompletely polymerized, and the unreacted portion is recycled to the process along with fresh charge stock. In such processes, the recycled unreacted olefins have substantially the same identity as the original olefins charged to the process, and these recycled olefins are accompanied by excessive amounts of inert material such as paraffin hydrocarbons, or elaborate olefin-paraffin separation steps must be incorporated in the process to get away from this objectionable material. In contrast, in the process of my invention only a particular olefin, propene, is recycled to the polymerization step, and the butenes are substantially completely converted. Any small amounts of unreacted butenes are not recycled directly to the polymerization step, but pass with butane to the dehydrogenation step. The propene may readily be separated in a relatively pure state by fractional distillation, both from the polymer product and from unreacted butane, which in its turn is readily separated from other hydrocarbons and can be

recycled in a relatively pure state to the dehydrogenation step.

My invention will now be described in connection with Figures 1 and 2, which together form a complete flow diagram and illustrate diagrammatically an arrangement of apparatus wherein my invention may be practiced.

A hydrocarbon stream comprising butanes, and which may comprise essentially pure isobutane, enters the system through conduit 16, and is compressed to a suitable pressure by pump 11. In many cases where isobutane comes directly from a fractional distillation, or other separation step, it may be under a pressure sufficiently high so that the pump 11 will not be necessary, and it may, of course, be omitted in such cases. Since a high superatmospheric pressure tends to affect the subsequent dehydrogenation adversely, the pressure should generally be only sufficient to overcome the pressure drop through the apparatus up to the compressor 41, and to provide a slight superatmospheric pressure at the inlet to this compressor. Such a pressure will not need to be in excess of 200 lbs./sq. in., and will generally be considerably less than that.

The isobutane, at a desired pressure, then passes through conduit 12, conduit 13 supplied with valve 14, to the transfer line heat exchanger 15, where it passes in indirect, counter-current heat exchange relationship with the effluent of the dehydrogenation to be described. From the heat exchanger 15 the stream passes through conduit 16 supplied with valve 17 to conduit 18, and on to the dehydrogenation step. With this arrangement, valve 21 in by-pass 22 is closed, but if desired all or any part of the stream may be diverted from the heat exchanger 15 through this by-pass by proper control of the valves 14, 17, and 21. From conduit 18 the stream passes through coils 23 located in the furnace 24. When the process is so operated that thermal dehydrogenation of the hydrocarbon stream is accomplished, these coils will be of such dimensions that the hydrocarbon stream is heated rapidly to a dehydrogenation temperature of the order of 1000 to 1250° F. and held within this temperature range for a period such that from about 10 to 40 mol per cent of the effluent material consists of normally gaseous olefin hydrocarbons. With such a procedure, the effluent of the coils 23 passes through conduit 25, controlled by valve 26, heat exchanger 15, conduit 27, cooler 28 and conduit 30 to the scrubber 31.

When it is desired to carry out a catalytic dehydrogenation, this may be done by opening valve 32 in conduit 33 and valve 34 in conduit 35, thus connecting the catalyst chambers 36 into the system, and closing valve 26. In the modification illustrated, the catalyst chambers 36 comprise relatively small tubes filled with a suitable dehydrogenation catalyst, and so located that large amounts of hot combustion gases pass over them. With this modification of operation, the relative volume of the coils 23 are such that the hydrocarbon stream is rapidly heated to a desirable reaction temperature, such as between about 850 to 1150° F., and passes directly into contact with the dehydrogenation catalyst. As reaction progresses, heat is absorbed, and this is made up by heat transfer from the combustion gases surrounding the catalyst tubes 36. Although only one source of heat in the furnace 24 is shown, it will be understood that additional burners solely for supplying heat to the catalyst tubes, or

other means for supplying heat to the catalyst and reactants at the desired temperature level, may be used. The dehydrogenation effluent passes from the catalyst chambers 36 through conduit 38 controlled by valve 34, and through conduit 25 to heat exchanger 15 and thence through the remainder of the apparatus as has been and will be described. If desired, preliminary thermal dehydrogenation may be obtained in coils 23, followed immediately by a catalytic dehydrogenation in the chambers 36.

In the scrubber 31 any carbon and/or tar is separated from the stream and removed through conduit 37 controlled by valve 38. This removal may be aided by the use of a heavy absorption oil or other means if desired, as will be evident to those skilled in the art, details pertinent to such a modification not being shown. The rest of the effluent stream, freed of such impurities, passes from scrubber 31 through conduit 40 to compressor 41, wherein it is compressed to a pressure of the order of 150 lb./sq. in. The compressed stream passes through conduit 42 to cooler and condenser 43 and through conduit 44 to separator 45.

Under the pressure developed by compressor 41 and at the temperature affected by cooler and condenser 43, most of the hydrocarbons having four and more carbon atoms per molecule, along with an appreciable proportion of propene and lighter hydrocarbons, will be condensed, and will be present in separator 45 in the liquid phase. This liquid hydrocarbon mixture which contains hydrocarbons to be polymerized, passes from the separator 45 through conduit 46, controlled by valve 47, to the polymerization-feed stripper or separator 50. The unliquefied material passes from scrubber 31 through conduit 48 controlled by valve 49.

The polymerization-feed stripper operates under a pressure slightly less than that existing in the separator 45, such as a pressure of about 125 lb./sq. in., so that an intermediate pump is not necessary. The stripper or separator 50 comprises essentially a fractionating column, heated at the bottom by conventional heating means, such as a steam coil 51. The top of the stripper is cooled by the expansion and vaporization of a liquid propene recycle stream, to be hereinafter described. A liquid hydrocarbon mixture comprising essentially propene, along with some propane formed and accumulated in the system, passes from the propene accumulator 52, which is equipped with a vent pipe 53 controlled by a valve 54, passes through conduit 55 to pump 56, and then through conduit 57 controlled by valve 58. As one method of operating, this propene stream may be introduced directly into the top of the separator 50 through an expander and spray nozzle 60.

At this point, a considerable amount of the stream is vaporized, producing a large refrigeration effect, the vapors passing up from the body of the separator are cooled by direct heat exchange in an efficient manner, and heavier constituents of these vapors are condensed to liquid. Uncondensed vapors, which comprise light hydrocarbons, a small amount of hydrogen which was dissolved in the stream passing through conduit 46, vaporized propene and propane, and only small amounts of butenes and butanes, passes from the stripper 50 through conduit 61 controlled by valve 62, and is mixed with the vapors passing from separator 45 through conduit 48. Not all of the propene is vaporized, but remains as a liquid and passes down the stripper along

with the liquid butenes and butanes so that the liquid at the bottom of the stripper contains, besides butenes and heavier hydrocarbons, appreciable amounts of the three-carbon hydrocarbons introduced through conduit 46 along with recycled three-carbon hydrocarbons. In this manner, after the process is in steady operation, it is possible that the relative amount of propene in the feed stock to the polymerization, to be described, will be appreciably higher than the relative amount of propene in the dehydrogenation effluent.

An alternative modification, not shown, by which this propene stream may be recycled and also used as a refrigerant, makes use of indirect heat exchange for cooling vapors from the top part of the polymerization-feed stripper. In this modification, the vapors from the top of the column are passed through a condenser and cooler in indirect heat exchange relationship with the expanding and vaporizing propene stream. The cooled, and partially condensed effluent is passed to a separator. From this separator a portion of the liquid is passed to the top of the stripper as a liquid reflux, while the vapors from the separator follow the same course as shown for the vapors passing from stripper 50 through conduit 61. The expanded and vaporized propene stream, now at a relatively low pressure, may be reintroduced to the system as recycle by passing it to the inlet of the scrubber 31. This specific modification is disclosed and claimed in the application of Hays and Maher, Serial No. 336,250, filed May 20, 1940. This is now Patent 2,351,123, issued June 13, 1944. Other modifications by which such a recycle propene stream may be used will now be obvious to those skilled in the art.

If it is desired to charge to the process a hydrocarbon mixture comprising both paraffins and olefins having three and four carbon atoms per molecule from an outside source, such as from cracking-still gases, this may be done by introducing such a mixture under a suitable pressure to conduit 46 by means of conduit 59 controlled by valve 64. In certain cases it may be desirable to have such a hydrocarbon mixture the principal or sole source of hydrocarbons charged to my process.

The feed or charge stock for the polymerization step, which consists essentially of hydrocarbons having three and four carbon atoms per molecule comprising both olefins and paraffins, and which is in the liquid phase, passes from stripper 50 through conduit 68. In one modification this stream passes through conduit 67 and valve 68 to pump 70, valve 66 in conduit 68 being closed. A portion of the propene stream coming from accumulator 52 through conduit 57 may be introduced at this point, being diverted from conduit 57 through conduit 71 controlled by valve 72. The liquid hydrocarbon mixture is compressed by pump 70 to a pressure suitable for subsequent catalytic polymerization of the olefins present therein, and the mixture passes through conduit 73 to heater 74 wherein the hydrocarbons are brought to a polymerization temperature. The mixture then passes through conduit 75 to the polymerization chamber 77. The effluent of chamber 77 passes through conduit 78 and valve 79 to a separating means such as the debutanizer 80.

An alternative, and not completely equivalent but often more preferable method of operating the polymerization step is to pass only a portion of the charge stock through conduit 67 to the polymerization chamber 77 as has been described,

and to pass another portion through valve 66 in conduit 68 to pump 81. From pump 81 the mixture passes through conduit 82 and valve 83 to heat-exchanger means 84, wherein the temperature is suitably adjusted, as will be discussed. From heat exchanger 84 the mixture passes through conduit 85 and valve 86 to manifold 88. It may at times be desirable for all or a portion of the hydrocarbon mixture not to pass through heat exchanger 84, and this may be by-passed by opening valve 88 in conduit 87 and partially or completely closing valves 83 and/or 86. From manifold 88 the mixture may be introduced at one or more points to the reaction mixture in contact with the polymerization catalyst, as by passing the mixture through one or more of the conduits 91, 92, 93 and 94 controlled by valves 95, 96, 97 and 98 respectively. Each of these conduits 91 to 94 may have individual heat exchanger means, not shown, whereby the temperature of each stream passed to the polymerization can be separately and independently controlled. Also a portion of the unheated material passing through conduit 87 may be added to the manifold 88 at some point further along its length such as between conduits 92 and 93, or the material may be separately mixed or blended by means of another manifold, not shown, with each of the individual streams flowing through these individual conduits, thus facilitating control of the temperatures of these streams. In place of using one long catalyst chamber, and adding these streams at various points throughout the length of this chamber, a number of smaller chambers may be used in series with the addition of a portion of the charge before each of the smaller chambers.

The introduction of a portion of the reactants at a plurality of points to the reaction mixture as it passes through a reaction zone, or at a plurality of points throughout the length of a reaction zone, has a number of advantages. The olefins to be polymerized are roughly divisible into two classes, a highly reactive class which includes isobutene, and a less reactive class which includes propene and any normal butenes and the like. I have found that when the reaction conditions are such that the less reactive olefins, considered by themselves, are only slightly or slowly polymerized, a considerable extent of copolymerization takes place when more reactive olefins are also present in the mixture, with the formation of copolymers, or hybrid polymers. This copolymerization is especially favored if the relative amount of the more reactive olefins, such as isobutene, is low, as has been previously discussed herein. The polymerization reaction is quite exothermic, so that the temperature of the reacting mixture, and the reactivity of the olefins to be polymerized, rises as the stream passes through the reaction zone. The arrangement of apparatus just described permits additional hydrocarbon material to be added to the reaction mixture, and at a temperature lower than that existing in the mixture at the point of the addition, so that the resultant mixture will be at a desirable reaction temperature. Such a procedure is described more fully in my copending application Serial No. 294,377, filed September 11, 1939, now Patent 2,377,411, issued June 5, 1945.

With any manner of adding initial reactants to the polymerization chamber, a further modification of operation may be practiced by passing a portion of the effluent of the polymerization directly back to the inlet of the polymerization chamber. In the apparatus shown, this can be

accomplished by partially opening valve 106 in conduit 101, which branches off of conduit 10, and recirculating a portion of the stream by means of pump 102 back to conduit 10. This modification is also more fully discussed in my copending application Serial No. 294,377.

In the separating means, or debutanizer, 80 the effluent of the polymerization is separated into two fractions, one consisting essentially of hydrocarbons having four and fewer carbon atoms per molecule, and the other fraction consisting essentially of hydrocarbons having more than four carbon atoms per molecule. This separation is effected and aided by bubble trays, or the like, not shown, heating means for the kettle represented by heating coil 103, and cooling means for the top represented by cooling coil 104. The lighter hydrocarbon fraction passes from the top of the debutanizer 80 in a vapor state through conduit 105 controlled by a valve 106, cooler 107, and conduit 108 to the separating means, or depropanizer, 110, the stream being compressed to a suitable pressure by a pump 109 located in conduit 108. This hydrocarbon mixture will consist essentially of unreacted butanes, principally isobutane, possibly along with small amounts of butenes, and of a considerable proportion of propane along with some propane. In separating means 110 a separation is made between the butanes and the lighter hydrocarbons. This is aided by bubble trays, not shown, heating means for the kettle represented by heating coil 111, and cooling means for the top represented by cooling coil 112. The butane fraction, comprising essentially isobutane, passes from the separating means 110 through conduit 113, controlled by a valve 114, and is passed to conduit 12 where it is mixed with fresh isobutane being charged to the dehydrogenation. A fraction containing propane and the like leaves the separating means 110 as a vapor through conduit 115, controlled by a valve 116, and passes through cooler and condensing means 117 and conduit 118 to the accumulator 52. Light or otherwise undesirable hydrocarbons may, from time to time be vented from the accumulator 52 through vent 53 controlled by a valve 56.

The hydrocarbon fraction containing olefin polymers passes from separating means 80 through conduit 120 and may be discharged from the system as desired, by opening valve 121. However, it will generally be treated further in the apparatus shown, by passing it from conduit 120 through conduit 122 controlled by a valve 123 to separating means 125, valve 121 being closed. In separating means 125, which may consist of a conventional fractionating column, a separation is made between lighter fractions of the polymer in the motor fuel boiling range, and heavier, higher boiling, hydrocarbons. This separation is aided by bubble trays, not shown, heating means for the kettle represented by heating coil 126, and cooling means for the top represented by cooling coil 127. The separation may also be aided by a reduced pressure on the hydrocarbons as may be effected by low pressure distillation or by steam distillation, either of which may be effected with additional apparatus, not shown, but obvious and well known to those skilled in the art. The lighter fraction, suitable for motor fuel, passes from the separating means 125 through conduit 128, controlled by valve 129, through cooler and condenser 130 and conduit 131 to the accumulator 132, from which it may be removed, as desired, through conduit 133 controlled by a valve 134.

The heavier hydrocarbon fraction, which comprises essentially olefin polymers in the upper part of the motor fuel boiling range, depending somewhat on the end-point of the fraction taken overhead through conduit 136, and polymers boiling above the motor fuel range, pass from separating means 135 through conduit 136, controlled by a valve 136, to an accumulator 137, and may be withdrawn therefrom as desired through conduit 140 controlled by a valve 141. These heavier polymers may be depolymerized by passing them at an elevated temperature and a relatively low pressure over a suitable catalyst which in certain cases, may be substantially the same as the polymerization catalyst used to polymerize the gaseous olefins. This depolymerization operation may be carried out by passing the heavy polymer from accumulator 137 through conduit 140, conduit 142 controlled by a valve 143, valve 141 being closed, to a pump 144 and thence through conduit 145 to heater 146, wherein they are heated to a temperature of the order of about 500 to 900° F., and then through conduit 147 to the chamber 148. A suitable depolymerization catalyst, not shown, is used in this chamber, and effects a depolymerization of the heavy polymer, forming hydrocarbons in the motor fuel boiling range along with lighter olefin hydrocarbons with little formation of extremely heavy hydrocarbons or of very light, saturated hydrocarbons such as methane and ethane. The effluent of this depolymerization is passed from the chamber 148 through conduit 150 controlled by a valve 151 to a separating means 152. Since the depolymerization operates under a low pressure, the pressure for separation may preferably be higher. The pressure on the material passing through conduit 150 may be readily raised by obvious means, not shown in detail. Separating means 152 may comprise a fractionator such as is known in the art, and if the sensible heat of the hydrocarbon stream passing through conduit 150 is not sufficient to heat the kettle product, additional heat may be added by suitable means such as the heating coil 153. Cooling at the top may be effected by an arrangement represented by cooling coil 154. A hydrocarbon fraction comprising hydrocarbons in the motor fuel boiling range passes from separating means 152 through a conduit 155 controlled by a valve 156, and through valve 157 to conduit 18 and are introduced into separating means 80. Heavier hydrocarbons in the boiling range of those charged to the depolymerization, are passed from separating means 152 through conduit 158 and may be discharged from the process through valve 159. However, it will generally be desirable to return all or a considerable amount of this fraction to the depolymerization, and this may be accomplished by opening valve 160 in conduit 161 and passing the stream to conduit 142, completely or partially closing valve 159. Material heavier than this recycle stream may be discharged from the process through conduit 162 controlled by valve 163, or if desired all or any part of this material may be recycled to the depolymerization step through conduit 164 controlled by a valve 165, passing to conduit 166 and finally to conduit 142, with proper control of valve 163. A hydrocarbon fraction too light to be included in motor fuel, may be discharged from the process through conduit 168 controlled by a valve 167. These hydrocarbons are generally suitable for polymerization, and as such may be passed from conduit 168 through conduit 170 controlled by valve 171 to conduit 80, thus being reintroduced to the process,

and eventually finding their way to the polymerization step in the liquid discharged from the polymerization-feed stripper 58 through conduit 85. In some cases, the life of the depolymerization catalyst may be increased by eliminating from the charge stock the heaviest part of the heavier polymers produced in the polymerization step. This may be accomplished by conventional fractionating means, not shown, which can be inserted in the first part of conduit 142, as will be understood by those skilled in the art.

The hydrocarbons in the motor fuel boiling range produced by my polymerization process are quite valuable as motor fuel, inasmuch as the individual hydrocarbons are highly branched in structure. This, and their olefinic properties, make the "blending" octane numbers of these hydrocarbons quite high. However, for some uses, such as for aviation motor fuel, it is much better to have a paraffinic motor fuel with a high octane number than to have a motor fuel which contains substantial amounts of olefin hydrocarbons. Since the olefin products of my process are highly branched, when they are subjected to nondestructive hydrogenation there results a paraffinic product having a high octane number, generally having a rating as determined by the ASTM method D347-34T of about 85 to 90 or better, and with a very good response to the addition of small amounts of tetraethyl lead or other detonation inhibitor. Inasmuch as considerable amounts of hydrogen are produced in the dehydrogenation of the gaseous paraffin charged to the process even when thermal dehydrogenation is used, a hydrogenation step can also be incorporated and cooperatively combined with my polymerization process.

The material passing in the gas phase from separator 45 through conduit 48 controlled by valve 49 contains hydrogen produced in the dehydrogenation step, along with some methane and other hydrocarbons, some of which will be olefins having three and four carbon atoms per molecule, and which are desired as charge stock to the polymerization step just described. To this material is added vapors from the polymerization-feed stripper 58 passing through conduit 61, and the resultant mixture is compressed by compressor 180 and passes through conduit 181, cooler and condenser 182, and conduit 183 to a separator 184. Higher boiling portions of the mixture are in the liquid state after this compression and cooling, and are separated in separator 184 from uncondensed portions. This liquid portion contains propene and butenes, and is removed from separator 184 through conduit 185 controlled by a valve 186 and passes to conduit 44 to be introduced to the separator 45. Constituents in the vapor phase pass from separator 184 through conduit 187 controlled by a valve 188 to a compressor 189, wherein they are compressed to a still higher pressure, and passed through conduit 190, cooler and condenser 191 and conduit 192 to separator 193. Again higher boiling constituents are liquefied, and this liquid fraction is passed from separator 193 through conduit 194 controlled by a valve 195 to the conduit 183, and is reintroduced into separator 184. The material which remains in the gaseous phase, and which now comprises an appreciable concentration of hydrogen and methane with only small amounts of heavier hydrocarbons, but which however, still contain some propene and butenes, passes from separator 183 through conduit 196 controlled by a valve 197 to the bottom of the absorber 200.

In the absorber 200 the material which has passed from the separator 183 in the gaseous state, which is now at an elevated pressure of the order of about 750 lb./sq. in., is contacted with lean absorption oil introduced at the top of the absorber through conduit 210. This absorption oil is introduced in such amounts that essentially all the hydrocarbons having three and more carbon atoms per molecule which are present in the material passing through conduit 183, along with much of the lighter hydrocarbons, are absorbed, and the residue gas containing principally hydrogen and methane passes from the absorber 200 through conduit 201. The rich absorption oil passes from the absorber 200 through conduit 202 controlled by a valve 203, to heater 204 and thence through conduit 205 to the top of the stripper 206, which it enters at a low pressure of the order of about 25 to 50 lb./sq. in. or less, and at a temperature of about 200° F. A portion of the residue gas from conduit 201 is passed through conduit 207 controlled by a valve 208 to the bottom of the stripper 206, and passes upward through the stripper counter current to the descending oil. The rich absorption oil entering through conduit 205 has essentially all the light hydrocarbons removed from it, and the resultant gaseous mixture passes from the top of the stripper through conduit 209, controlled by a valve 210, to conduit 170 and on to conduit 30, whereby valuable propene and butenes removed by the absorption oil in the absorber 200 are returned to the system. The resultant lean absorption oil leaves the stripper through conduit 211, controlled by a valve 212, through cooler 213 and conduit 214 to an accumulator 215. From the accumulator the absorption oil is removed through conduit 216, controlled by a valve 217 and is pumped by pump 218 through conduit 219 and valve 220 to the top of absorber 200.

The gas passing through conduit 201 has a high content of free hydrogen, and may be partially or completely used in the hydrogenation to be described by passing the amount desired from conduit 201 to conduit 230 through by-pass 234 controlled by a valve 235. However, the material other than free hydrogen, is substantially only hydrocarbon material, and this may be removed or greatly decreased in amount, by a conventional oil absorption system, if such is desired.

A portion of the lean absorption oil is passed from conduit 219 through conduit 221 controlled by a valve 222 to the top of an absorber 223. Part or all of the gas remaining in conduit 201 is passed through valve 225 to the bottom of the absorber 223. Any undesired portion of this gas may be removed from the system through conduit 226 controlled by a valve 227, and at times a part may be directly passed through conduit 234 and valve 235. In the absorber 223 most of the hydrocarbon material is removed from the gas, leaving substantially pure hydrogen. This hydrogen passes from the absorber 223 through conduit 236 controlled by a valve 231, and may be passed to the hydrogenation step to be described, or may be removed from the system for other uses as may be desired through conduit 232 controlled by a valve 233. The rich absorption oil leaves the bottom of this second absorber through conduit 236 controlled by a valve 237, and is passed to the top of the stripper 206, wherein light hydrocarbons it has absorbed in absorber 223 are removed and pass from the system, together with any stripping gas used, through conduit 240 controlled by a valve 241.

As stripping gas some of the excess hydrogen and gases from the separator passing through conduit 275 may be used, or gases from any other source, not shown, may be used. The lean oil passes from the stripper 238 through conduit 242, controlled by a valve 243, to conduit 211 and accumulator 215.

When it is desired to saturate the polymers in the motor fuel boiling range produced in the polymerization step and available in the accumulator 132, this may be done by passing this material through conduit 133 and through conduit 250, controlled by a valve 251, to a pump 252, and then through conduit 253. Hydrogen passing through conduit 230 is compressed by pump or compressor 254 and passes through conduit 255 to be mixed with the material passing through conduit 253. If desired, saturated hydrocarbons may be added as a diluent, these passing from conduit 271 through conduit 256, controlled by a valve 257, to pump 258, and then through conduit 259 to conduit 270. The combined mixture then passes through heater 260 and conduit 261 to the hydrogenation chamber 262. The mixture is heated to a suitable initial reaction temperature in heater 260 and is passed over a body of a hydrogenation catalyst, not shown, in the hydrogenation chamber 262. Hydrogen is added to the unsaturated linkages of the unsaturated hydrocarbons, and the effluent, comprising essentially excess hydrogen and paraffin hydrocarbons having the same general boiling range as the unsaturated hydrocarbons charged to the process, passes from the hydrogenation chamber through conduit 263, controlled by a valve 264, to a high pressure separator 265. In this high pressure separator a separation is made between a liquid phase and a gas phase which comprises substantially excess hydrogen plus light gases originally accompanying the hydrogen. This separation is aided by cooling means in the top of the separator, such as the cooling coil 266. This excess hydrogen is passed from the top of the separator through conduit 267 and is returned to the hydrogenation through valve 268, compressor 269 and conduit 270 to conduit 255. The material in the liquid state passes from the separator 265 through conduit 271, controlled by valve 272, to the low pressure separator 273, wherein hydrogen dissolved at the high pressure in the liquid material flowing through conduit 271, along with any light hydrocarbons, is released and separated. This separation is aided by cooling means in the top of the separator, such as the cooling coil 274, which condenses hydrocarbons in the motor fuel boiling range which have vaporized. Released hydrogen, along with any light hydrocarbons, passes from the low pressure separator 273 through conduit 275 controlled by a valve 276, and may be passed through valve 276 to the bottom of stripper 238 to be used as a stripping gas, as previously mentioned, and is finally discharged from the system. If desired, all or a part of this stream may be returned to the system for recovery of the hydrogen, by passing it through by-pass conduit 277 and valve 278 to conduit 170 and eventually to conduit 30. Any part of the hydrogen separated in the high pressure separator 265 which is not recirculated may be passed from conduit 267 to conduit 275 through conduit 284 controlled by valve 285.

A hydrocarbon mixture, which comprises essentially paraffin hydrocarbons in the motor fuel range which have highly branched structures, is recovered as a desired product from the low

pressure separator through conduit 286, controlled by a valve 281.

The dehydrogenation step of my process may be either thermal or catalytic, or a combination of both, but in any case it should be at as low a pressure as is practicable. While a subatmospheric pressure may at times be most desirable, it is generally more practical to operate this step at a slight superatmospheric pressure, which I prefer not to have exceed about 200 lb./sq. in., and which preferably should only be sufficiently high to insure adequate flow through the apparatus. With an active dehydrogenation catalyst, the temperature may be as low as 750° F., but I prefer to perform catalytic dehydrogenation at between 850 and 1150° F. If the dehydrogenation is to be thermal, somewhat higher temperatures, up to about 1300° F. should be used, with a preferred range for thermal dehydrogenation lying between 1000 and 1250° F. In any case, the reaction time should be such that between about 10 and 40 mol per cent of the effluent consists of catalytically polymerizable gaseous olefins, preferably about 20 mol per cent, and such that secondary reactions of the dehydrogenation products do not take place to any appreciable extent. When catalysts are used, I prefer that they should be of the chromium oxide type, as disclosed in U. S. Patents 1,905,383 or 2,098,959, or in the copending application of Matuszak and Morey filed November 9, 1937, Serial No. 173,708, now Patent 2,294,414, issued September 1, 1942, or of the bauxite type such as disclosed in Schulze 2,167,602.

As stated more explicitly hereinbefore, the conditions for polymerization should be such that propene is only slowly polymerized with itself, and the effluent should contain very little unreacted butenes. Specifically, the pressure on this step should be not less than about 200 lb./sq. in. and preferably is somewhat higher, such as in the range of 600 to 1800 lb./sq. in., and may be as high as 3000 lb./sq. in. or more. The polymerization temperature should generally be in excess of 75° F., and I prefer to operate in the range of 150 to 400° F., although at times, and especially near the end of a run with a given batch of catalyst, when it has become somewhat deactivated, I may operate my process at polymerization temperatures as high as about 600° F. The flow rate will generally be between about 5 and 20 volumes of liquid hydrocarbon charged per hour per volume of catalyst, that is, the actual volume of the catalyst particles plus the voids inherently present.

The process is not especially dependent on the use of any particular polymerization catalyst, except that the catalyst used preferably should be of a type which has a minimum tendency to promote, under the reaction conditions used, reactions other than the union of olefin hydrocarbons to form olefin polymers, such as cyclization reactions, dehydrogenation reactions, and the like. I prefer to use a catalyst similar to the silica-alumina catalyst hereinafter more completely described and discussed but other catalysts may also be used, such as the well known "solid" phosphoric acid catalysts, catalysts comprising metal phosphates, and the like. It is also not necessary to use a solid catalyst, and catalysts such as liquid sulfuric acid and the like may also be used. Such a liquid catalyst will necessitate certain additional apparatus which has not been shown but which is well known to those skilled in the art and which can be readily sub-

stituted. It will also be obvious that, when solid catalysts are used, the chamber 17 shown is only a diagrammatic representation, and that in actual practice a number of chambers may be used, in series or in parallel, with other catalyst chambers containing fresh or reactivated bodies of catalyst, or bodies of catalyst undergoing reactivation or regeneration so that as the body of catalyst being used becomes deactivated, the process may be continued with fresh catalyst without more than temporary interruption. This same comment, of course, applies to any dehydrogenation or dehydrogenation catalyst which may be used in the process.

The hydrogenation step should be carried out catalytically, and any known catalyst which will effect a non-destructive hydrogenation of unsaturated hydrocarbons may be used. I have been able to obtain very satisfactory hydrogenation of the olefins produced in my process by passing them, in the presence of hydrogen, over a nickel-copper-alumina catalyst such as has been disclosed by Thomas G. Strickland in his copending application Serial No. 240,196, filed November 12, 1938, now Patent 2,242,627, issued May 20, 1941. In general, the hydrogenation temperature will be between about 100 and 650° F., preferably between about 200 and 600° F., and is carried out at a superatmospheric pressure which may be as high as 2000 lb./sq. in. or more, but which will generally be between about 200 and 800 lb./sq. in. The hydrogenation may be carried out in a catalyst chamber which consists of a number of small, catalyst-filled tubes which are surrounded by a cooling medium such as is well known in the art. However, I have been able to effect the nondestructive hydrogenation of normally liquid unsaturated hydrocarbons by mixing with the unsaturated hydrocarbons from 1 to 5 or more volumes of saturated hydrocarbons having the same boiling range, and passing the mixture, with an excess of free hydrogen, at a hydrogenation temperature, over a body of a solid nickel-containing hydrogenation catalyst, and maintaining a pressure such that the major part of the hydrocarbon material charged to the process is in the liquid phase at the hydrogenation temperature which is maintained at the inlet to the catalytic hydrogenation chamber. As hydrogenation proceeds and the heat of reaction is liberated, a part of the hydrocarbon material is vaporized and this heat of reaction is taken up as latent heat of vaporization, without undue temperature rise of the reactants. Such a process is disclosed in detail in my copending application Serial No. 299,219, filed October 12, 1939, now U. S. Patent 2,303,118, issued November 24, 1942.

Another liquid phase hydrogenation process for the non-destructive hydrogenation of unsaturated hydrocarbons in the motor fuel boiling range, which may be incorporated with my process, and in which liquid butane or the like is used as a material which vaporizes from the reacting mixture and absorbs heat of reaction, is disclosed in the copending application of Harold J. Hepp and Jean P. Jones, Serial No. 327,518, filed April 2, 1940, now Patent 2,332,572, issued October 26, 1943. Still another process is disclosed in my copending application Serial No. 240,195, filed November 12, 1938, now U. S. Patent 2,303,075, issued November 24, 1942.

While the depolymerization step may be carried out in the absence of a catalyst, I prefer that it should be a catalytic depolymerization.

I have found that the silica-alumina catalyst, herein described, is a good depolymerization catalyst as well as a polymerization catalyst, and I prefer to use it when the depolymerization step is a part of my process. Other catalysts which may also be used include bauxite, various natural aluminum silicates, activated alumina, and the like. The pressure should be as low as possible, and while it may be subatmospheric, it will be preferable to use a slight superatmospheric pressure, such as 30 to 50 pounds/sq. in. gauge, and which should not be in excess of about 100 lb./sq. in. The temperature may be between 500 and 900° F., and will generally be in the upper part of the range such as between 700 and 850° F. The heating of the charge stock to the reaction temperature should be as rapid as possible, especially when the temperature at the inlet to the reaction chamber is in the upper part of the range given, so that uncatalyzed decomposition of the hydrocarbons will be at a minimum. The reaction is quite endothermic, but although it may be desirable to operate so that the catalyst mass is in heat-exchange relationship with a heat-supplying medium, I have found that satisfactory results may be obtained by using a single body of catalyst and heating the charge stock to within the upper part of the range given. The reaction time will be roughly in an inverse relationship with the temperature, and at higher temperatures a reaction time somewhat shorter than that which will produce maximum depolymerization is preferred, in order not to decrease the activity of the catalyst too rapidly. I have obtained satisfactory results with a flow rate of the total charge, that is fresh charge plus recycled material, between 0.5 and 5 liquid volumes per volume of catalyst per hour.

As an example of the operation of one modification of my process, a hydrocarbon mixture comprising essentially pure isobutane, as represented by the analysis given in column 1 of Table I, was mixed with about 2.5 times as much recycled isobutane, and was passed through the thermal dehydrogenation coil 23, by-passing the catalyst chambers 36. A dehydrogenation temperature between 1150 and 1220° F. was maintained, a gauge pressure of about 25 lb./sq. in. being maintained at the exit of this dehydrogenation section. The effluent, which had the composition shown in column 3, was passed to separator 45 and separated into liquid and vaporous portions, the liquid portion having the composition shown in column 4. This mixture was passed to the polymerization-feed stripper 50, which was suitably heated at the bottom and was cooled at the top by the direct introduction of recycle liquid propene from accumulator 52, which was partially vaporized at 60, and which had the composition shown in column 7.

60 A hydrocarbon mixture comprising propene and butenes, containing recycled propene from the unvaporized portion of the material introduced at 60 and a portion of the vaporized propene which had been recovered in separator 45, and having the composition shown in column 5, was passed to the polymerization catalyst.

An olefin polymerization catalyst comprising alumina associated with silica, and which will be spoken of as a "silica-alumina catalyst" was prepared by first forming a silica gel from a liquid sodium silicate of 41° Bé. gravity containing 8.9 per cent Na₂O, 28.5 per cent SiO₂, and 62.6 per cent H₂O, and from commercial sulfuric acid of 66° Bé. gravity. The sodium silicate solution, or 70 "water-glass" was diluted by adding 1.5 volumes

of water and the acid was diluted with 7 volumes of water. Equal volumes of these two resulting solutions were mixed by rapidly flowing the sodium silicate solution into the acid solution with thorough stirring. The mixture was then allowed to stand overnight, and had set and stiffened to a firm gel about 12 hours after mixing the solutions. This gel was broken up by forcing it through a coarse screen of about one inch mesh, was washed for 16 hours, and was then partially dried in hot air to a degree sufficient to shrink the gel only to a point where it attained sufficient rigidity to ring slightly when tumbled. It was again washed and then treated with boiling water containing in solution about 5.5 per cent of aluminum sulfate, the treatment continuing for about 2 hours. The gel was washed, partially dried and again treated with an aluminum sulfate solution. After this treatment, the treated gel was washed with water until the effluent wash water was substantially free of sulfate, but care was taken to insure that the wash water was not alkaline. After this treatment the activated gel was thoroughly dried, and was then classified as to size. In this manner of preparation, a limited amount of alumina was thoroughly and intimately incorporated with silica, forming a silica-alumina catalyst which is quite efficient in promoting the polymerization of normally gaseous olefin hydrocarbons to polymers in the motor-fuel boiling range.

The catalyst was classified as to size in three different batches; (1) larger than 12 mesh, (2) between 12 and 20 mesh, and (3) between 20 and 35 mesh, and was then placed in the chamber with the finest catalyst on the bottom, the intermediate in the middle, and the coarsest catalyst on top. It has been found that this procedure results in a decrease in the pressure drop which would occur if unclassified catalysts were used, and also results in a condition of greatest pressure drop near the bottom of the catalyst bed, which lessens the tendency of the mass of catalyst to become packed. Such an operation is disclosed by Karl H. Hachmuth in U. S. Patent 2,283,499, issued May 19, 1942.

After the catalyst chamber was filled, a stream of propane was passed through the chamber at about 250° F. which further dried the catalyst and displaced all the air. At the beginning of a period of use of a fresh batch of catalyst, the hydrocarbon stream from the bottom of the polymerization-feed stripper 50 was heated to a temperature of about 220° F., under a pressure of about 1500 lbs./sq. in. and passed over the silica-alumina catalyst at a rate of about 5 volumes per hour per volume of catalyst, which was found to insure a minimum of unreacted butenes in the effluent. As the catalyst decreased in activity, the temperature of the hydrocarbon stream charged to this step of the process was raised, providing thereby a constant amount of polymerization. This was continued until a final temperature of about 600° F. was reached, at which time the catalyst was judged to be inactive, and the process was continued at a lower temperature using a fresh batch of catalyst. The effluent of the polymerization catalyst had the composition shown in column 6. This effluent was passed to separating means, and there was separated a propene-recycle fraction, an isobutane fraction, and a fraction comprising normally liquid hydrocarbons in the motor fuel boiling range. When the polymerization temperature was in the range of about 570° F., the polymer and motor fuel frac-

tions had the compositions shown in Table II. It will be seen that although this was not a particularly favorable temperature, nevertheless a substantial portion of the polymer had been formed by the copolymerization of propene and isobutene. The fraction in the motor fuel boiling range was passed over a nickel-containing hydrogenation catalyst at a pressure of about 700 lb./sq. in., and a temperature of about 300° F., in the presence of free hydrogen-containing gases produced by the dehydrogenation step and passing from absorber 223 through conduit 230, the composition being about as shown in column 8 of Table I. The hydrogenated motor fuel produced from polymer formed at about 300° F. had the characteristics shown in the last part of Table II. In addition to having a high octane number, it was quite responsive to the addition of small amounts of tetraethyl-lead.

As an example of the operation of the depolymerization step of my process, the total heavy polymer boiling above 333° F., produced in a process as just described and consisting of about 15 per cent of the total polymer, was depolymerized over a granular silica-alumina catalyst prepared as hereinbefore described. The charge stock, with between 1 and 5 times an equivalent amount of recycled heavy material, was passed at a gauge pressure of about 5 pounds per sq. in. over a silica-alumina catalyst at a temperature between 570 and 850° F., and at a rate of about 1 liquid volume of fresh charge per volume of catalyst per hour. The yield was as given in Table III. The heaviest part of the heavy residue in the effluent was discarded, and the remainder of the heavy residue was recycled to the depolymerization. The gas consisted essentially of isobutene which could be sent back to the polymerization step, and the gasoline so produced, after hydrogenation, had an octane number of 80.8 (ASTM D 357-34T).

	100.0	100.0

Numerous materials comprising compounds of aluminum and silicon, or mixtures of compounds of these elements such as mixtures of their oxides, with or without small amounts of other materials which may act as promoting agents, have been proposed for use as catalysts in various processes for treating hydrocarbons. Among these compounds are various natural and artificial aluminum silicates, some of which have been proposed for use in the polymerization of gaseous olefins. Synthetic aluminum silicates may be prepared by the interaction of aluminum chloride, or other aluminum salt, with sodium silicate, or "water glass." While some of these synthetic aluminum silicates have good activity as polymerization catalysts, their physical form is poor, the silicate being a fine powder difficult to retain against a fluid flow, and many of them must be briquetted or extruded into pellets before being used.

However, synthetic catalysts of the gel type, or dried-gel type, such as the silica-alumina catalyst specifically described herein, have excellent physical properties, being somewhat similar to ordinary sand in gross physical appearance, and their activity in the polymerization of olefins is generally much better than that of either natural or synthetic aluminum silicates. Although a silica-alumina catalyst may be made by other modifications than that specifically given herein, the manner of preparation will generally comprise essentially the preparation of a highly hydrous gel, or standing jelly, of silica, such as is well known in the art, washing this gel with water to remove a substantial amount of water soluble material, with or without partial drying but

without drying to a water content of less than about 40 or 45% of water, and treating this gel with an aqueous solution known as an activating solution, containing an aluminum salt, such as aluminum chloride, sulfate or nitrate. In this treatment it appears that the aluminum is preferentially adsorbed on, or otherwise associated with the silica, and during the treatment the aluminum content of the activating solution decreases markedly while the pH also decreases. Small amounts of other salts may be included in this activating solution, such as water-soluble salts of zinc, cadmium, beryllium, and the like, in which case the final silica-alumina catalyst will also contain small amounts of these other metals, and it is assumed that these modifications comprise the oxides of these other metals, in the same manner as the aluminum is assumed to be present as alumina. Although it is not known for sure in just what manner the activation of the silica gel with the aluminum salt solution takes place, the catalyst appears to contain aluminum oxide, or alumina, associated with the silica, and for this reason it is referred to as a silica-alumina catalyst. After the activation treatment, the material is washed and dried, and may finally be dehydrated at an elevated temperature. A modification includes drying the treated material only partially, and then subjecting it again to the action of an activating solution, following this by further washing with water, and drying.

A silica-alumina catalyst prepared in this manner from a firm, hydrous silica gel, is substantially a dried gel, and has been found to be superior, both from a physical standpoint as well as from a standpoint of catalytic activity, to a material comprising silica and alumina prepared from a silica which is more or less of a loosely aggregated or chalky precipitate. This silica-alumina catalyst, while it may be finely ground and briquetted, or made into various large particles by extrusion, is quite readily used, and may be handled as particles of an ordinary and desired size, without such preparation merely by breaking up the larger particles of dried gel, and screening or sieving to a desired size.

During use, the silica-alumina catalyst gradually loses activity, but this may be restored in any one of a number of ways. The deactivation is accompanied by a deposition of carbonaceous material and this may be removed by burning it off in an atmosphere containing free oxygen. Preferably, this type of regeneration, or revivification, is carried out with a very low initial concentration or partial pressure of free oxygen, such as 0.1 atmosphere of pressure, and also with only small amounts of water vapor. As the revivification progresses, the oxygen partial pressure is increased, but it has been found to be preferable to maintain the partial pressure of the water vapor at a continuously low value.

Other means of regeneration or revivification include treatment of the deactivated catalyst with alkyl halides, treatment with a hydrogen halide, and treatment with an aqueous solution of an aluminum salt. Particles which are too fine for use, or portions of the catalyst which are deactivated, may be recovered by dissolving such material with a strong caustic solution such as sodium or potassium hydroxide, whereby a sodium silicate is formed which may be used in the production of fresh catalyst.

While my invention has been more particularly described in connection with the dehydrogenation of isobutane, and with the subsequent treatment

of the catalytically polymerizable olefins thereby produced, it is to be understood that I do not necessarily wish to be so limited in every instance. Also I do not wish to be limited at all times to the thermal dehydrogenation herein specifically described, for as discussed, I may also use any one of numerous various known dehydrogenation catalysts. Also I may use a combination of thermal and catalytic dehydrogenation, which is especially efficient when the charge stock to the dehydrogenation step contains about 35 percent or more normal butane. Also, if a charge stock is available which contains appreciable amounts of both propene and butenes, it may be charged directly to the polymerization step, such as through the conduit 58 to the polymerization feed stripper 50, or more directly to conduit 65 through means not shown. In this latter case, the butanes present in such a charge stock could be sent to the dehydrogenation step, the desirable portion of the effluent being finally separated in the polymerization feed stripper, as discussed. In any case, recycled propene can be added to the stream charged to the polymerization catalyst through conduit 71.

Even when absolutely pure isobutane is charged to the dehydrogenation step, appreciable amounts of propane will be formed with the propene, probably in a manner which includes concomitant hydrogenation of the propene produced. In the system as shown, excessive build-up of propane has been successfully controlled by occasionally venting gases through conduit 58. However, if the amount of propane becomes excessive, or if too much propene is lost in this manner, or if considerable amounts of propane are introduced to the system along with unsaturated charge stock charged directly to the polymerization step, the separating means shown may be supplemented by the inclusion of a step for separating propene from propane and reintroducing propene into the system as recycle stock. This separation may be carried out by any known means such as selective solvent action, or the like, and can be readily incorporated in the process by any one skilled in the art. These and other obvious modifications can be made in the process by those skilled in the art without changing the nature of my invention.

What I claim is:

1. A process for producing normally liquid hydrocarbons of branched structure, which comprises subjecting a hydrocarbon mixture comprised predominantly of butane to dehydrogenation at a lower pressure and a dehydrogenation temperature not in excess of 1300° F. to produce butenes and propene, separating from the effluent a hydrocarbon fraction comprising hydrocarbons having three and four carbon atoms per molecule, dividing said fraction into at least two portions, adding to one of said portions a recycle hydrocarbon mixture comprising predominantly propene to provide a mixture having a molecular excess of propene over butenes and subjecting the resultant mixture to the action of an olefin polymerization catalyst at a polymerization temperature between about 75 and 600° F. to copolymerize and convert the butenes and propene into liquid hydrocarbons, adding other portions of said fraction to the mixture undergoing polymerization at a plurality of points, removing from the effluent of said polymerization catalyst a fraction comprising normally liquid hydrocarbons so produced and removing said fraction from the process, separating also a fraction comprising predominantly

unreacted propene and returning said fraction as said recycle hydrocarbon mixture to be mixed with hydrocarbons initially charged to said polymerization catalyst.

5 2. A process for producing normally liquid aliphatic hydrocarbons of branched structure, which comprises subjecting a hydrocarbon mixture comprised predominantly of isobutane to dehydrogenation at a pressure of less than 200 pounds per square inch and a dehydrogenation temperature not greater than about 1300° F. to produce isobutene and propene, separating from the effluent a hydrocarbon mixture comprising essentially hydrocarbons having three and four carbon atoms per molecule, dividing said fraction into at least two portions, adding to one of said portions a recycle hydrocarbon mixture comprising propene and subjecting the resultant mixture to the action of an olefin polymerization catalyst at a polymerization temperature and pressure to copolymerize isobutene and propene into liquid hydrocarbons, adding other portions of said fraction at a plurality of points to the hydrocarbon mixture undergoing polymerization, separating a portion of the effluent and returning said portion directly to said polymerization catalyst, separating from another portion of said effluent a fraction comprising liquid hydrocarbons in the motor fuel boiling range so produced and removing said fraction from the effluent, and separating also a fraction comprising predominantly unreacted propene and returning said fraction to the action of said polymerization catalyst.

3. A process for producing normally liquid hydrocarbons in the motor fuel boiling range, which comprises subjecting a normally gaseous hydrocarbon mixture comprising isobutene to thermal dehydrogenation at a low pressure and a dehydrogenation temperature not greater than 1300° F. to produce isobutene and propene, separating from the products a hydrocarbon mixture comprising olefin hydrocarbons having three and four carbon atoms per molecule, adding to at least a portion of said mixture a recycle hydrocarbon mixture comprising propene, subjecting the resultant mixture to the action of a silica-alumina polymerization catalyst at a polymerization temperature and pressure to copolymerize isobutene and propene forming normally liquid hydrocarbons some of which boil in the motor fuel range and some of which boil above the motor fuel range, passing at least a portion of the effluent of said polymerization step to separating means, separating from said effluent a fraction comprising hydrocarbons in the motor fuel boiling range and removing said fraction from the process, separating a fraction comprising propene and returning said fraction to the said polymerization step, separating also a fraction comprising olefin polymers boiling above the motor fuel range, passing the last said fraction at a low pressure and a reaction temperature over a silica-alumina catalyst to depolymerize said olefin polymers forming lower boiling hydrocarbons, passing the effluent to a second separating means, separating from said effluent a hydrocarbon fraction comprising hydrocarbons in the motor fuel boiling range and passing said fraction to the first said separating means, and separating also a fraction comprising olefin hydrocarbons boiling lower than the motor fuel range and passing the last fraction to said polymerization step.

4. A process for producing normally liquid hydrocarbons of branched structure, which comprises subjecting a normally gaseous hydrocar-

23

bon mixture comprised predominantly of butane to dehydrogenation at a low pressure and a dehydrogenation temperature not in excess of 1300° F. to produce butenes and propene, separating from the effluent a hydrocarbon mixture comprising hydrocarbons having three and four carbon atoms per molecule, dividing said fraction into at least two portions, adding to one of said portions a recycle hydrocarbon mixture comprising predominantly propene and subjecting the resultant mixture to the action of an olefin polymerization catalyst at a temperature between about 75 and 600° F. to copolymerize and convert the butenes and propene into liquid hydrocarbons under conditions such that the butenes are substantially completely polymerized, adding other portions of said fraction to the mixture undergoing polymerization at a plurality of points, removing from the effluent of said polymerization catalyst a fraction comprising normally liquid hydrocarbons so produced and removing said fraction from the process, separating by fractional distillation a fraction comprising predominantly unreacted propene, returning said fraction to be mixed with hydrocarbons initially charged to said polymerization catalyst as said recycle hydrocarbon mixture, separating also by fractional distillation a predominantly paraffinic fraction comprising essentially four carbon atom hydrocarbons and returning said fraction to be mixed with the hydrocarbons subjected to dehydrogenation.

5. A process for producing normally liquid hydrocarbons in the motor fuel boiling range, which comprises subjecting a normally gaseous hydrocarbon mixture comprising isobutane to thermal dehydrogenation at a low pressure and a dehydrogenation temperature not greater than 1300° F. to produce isobutene and propene in a molecular ratio between about 0.5:1 and 2:1, separating from the products a hydrocarbon mixture comprising olefin hydrocarbons having three and four carbon atoms per molecule, adding to at least a portion of said mixture a recycle hydrocarbon mixture comprising a high concentration 45 of propene in an amount such that the molecular ratio of propene to butenes in the total mixture is between about 1:1 and 4:1, subjecting said mixture to a silica-alumina polymerization catalyst, maintaining a pressure on the polymerization step between about 200 and 3000 pounds per square inch, a polymerization temperature between about 75 and 600° F. and such that propene is only slowly polymerized with itself, and a reaction time such that unreacted butenes are 55 substantially absent in the effluent and normally liquid hydrocarbons some of which boil in the motor fuel range and some of which boil above the motor fuel range are formed, passing at least a portion of the effluent of said polymerization step to separating means, separating from said effluent a fraction comprising hydrocarbons in the motor fuel boiling range and removing said fraction from the process, separating a fraction comprising propene in high concentration and returning said fraction to the said polymerization

24

step as said recycle hydrocarbon mixture, separating also a fraction comprising olefin polymers boiling above the motor fuel range, passing the last said fraction at a low pressure and a reaction temperature over a silica-alumina catalyst to depolymerize said olefin polymers forming lower boiling hydrocarbons, passing the effluent to a second separating means, separating from said effluent a hydrocarbon fraction comprising hydrocarbons in the motor fuel boiling range and passing said fraction to the first said separating means, and separating also a fraction comprising olefin hydrocarbons boiling lower than the motor fuel range and passing the last fraction to said polymerization step.

6. A process for producing normally liquid aliphatic hydrocarbons of branched structure and boiling in the motor fuel range from propene and butenes, which comprises dividing into at least 20 two portions a hydrocarbon mixture comprising propene and butenes in a molecular ratio less than 1:1, adding to one of said portions a recycle hydrocarbon mixture comprising propene to provide a mixture having a molecular excess of propene over butenes and subjecting the resulting mixture to the action of an olefin polymerization catalyst at a polymerization temperature between about 75 and 600° F. to copolymerize and convert butenes and propene into liquid hydrocarbons, adding other portions of the first said hydrocarbon mixture at a plurality of points to the mixture undergoing polymerization, separating from effluents of said polymerization catalyst a hydrocarbon fraction comprising normally liquid hydrocarbons so produced and removing said fraction from the process, separating also from said effluents a fraction comprising unreacted propene and returning said fraction as said recycle hydrocarbon mixture to be mixed with the hydrocarbons initially charged to said polymerization catalyst.

Certificate of Correction

Patent No. 2,427,954.

September 23, 1947.

FREDERICK E. FREY

It is hereby certified that errors appear in the printed specification of the above numbered patent requiring correction as follows: Column 1, line 40, for "hydrocarobns" read *hydrocarbons*; column 2, line 39, for "rich is" read *rich in*; column 4, line 14, for "true of" read *true if*; column 15, line 13, for "dehydrogenation" read *hydrogenation*; column 21, line 55, claim 1, for "lower" read *low*; column 22, line 37, claim 3, for "isobutene" read *isobutane*; and that the said Letters Patent should be read with these corrections therein that the same may conform to the record of the case in the Patent Office.

Signed and sealed this 30th day of December, A. D. 1947.

[SEAL]

THOMAS F. MURPHY,
Assistant Commissioner of Patents.
